ABSTRACT OF THE DISCLOSURE

The disclosure deals with 17-dihydroxy-(lower) alkoxy-estratriene dinitrates which have been found to possess pharmacological activity, particularly as blood pressure lowering agents.

15

This is a continuation-in-part of our application, Ser. No. 538,982, filed Mar. 31, 1966, now abandoned.

This invention relates to and has for its objects the provision of new physiologically active compounds, novel processes for their production and new intermediates useful in the preparation thereof.

More particularly this invention relates to compounds of the Formula I:

wherein R is selected from the group consisting of lower alkyl of less than eight carbon atoms (e.g., methyl, ethyl, n-propyl, isopropyl, butyl, etc.) acyl and monocyclic cycloalkyl (e.g., cyclopropyl, cyclobutyl, cyclopentyl, cyclohexyl, etc.); R¹ is a lower alkyl group of less than eight carbon atoms (e.g., methyl, ethyl, propyl, butyl, etc.) but preferably from 1 to 4 carbon atoms; R² is selected from the group consisting of hydrogen and lower alkyl of less than 5 carbon atoms (e.g., methyl, ethyl, propyl, butyl) but preferably hydrogen; and n is 1, 2 or 3, preferably 1.

Among the suitable acyls may be mentioned the acyl radical of a hydrocarbon carboxylic acid of less than 12 carbon atoms, as exemplified by the lower alkanoic acids (e.g., acetic, propionic, butyric, hexanoic and enanthic acid), the cycloalkane carboxylic acids (e.g., cyclobutane carboxylic acid), the monocyclic aromatic carboxylic acids (e.g., benzoic) and the monocyclic aryl lower alkanoic acids (e.g., phenacetic and β -phenylpropionic acid).

The final products of this invention are physiologically active substances having blood pressure lowering activity and which may be used as vasodilators in experimental pharmacology or for veterinary or human use.

In pharmacology, the compounds are preferably used intravenously although it is contemplated that they may also be used orally or parenterally (e.g., subcutaneously) in veterinary or human medicine. Compositions containing active ingredients may be made up in standard dosage forms, generally with an inert excipient or carrier.

The blood pressure lowering effect was noted in the standard test animal (cat) within the dosage range of 5 to 10 mg./kg. of body weight. A test procedure to elicit blood pressure effects may be described as follows.

2

Cats are anesthetized with a standard agent, for example, Dial-urethane (Ciba). Blood pressure and heart rate are recorded. The test drug is injected intravenously (in most cases) in doses of 0.1, 1, 5, and 10 mg./kg. at intervals of 30 to 60 minutes depending on the time when blood pressure has been returned to the control level. Maximal changes in blood pressure are noted.

It may be pointed out that if the compounds are to be used for other than experimental purposes, the initial dose is best kept at the lowest portion of the indicated dosage range and then adjusted to the requirements of the animal or person treated. This is generally the case with vasodilators since the proper dose can only be determined on an individual basis.

The compounds of this invention can be prepared by employing the novel processes of this invention beginning with the compounds of the Formula II:

wherein R, R¹, R², and n are as hereinbefore defined as starting material. The starting material of this invention may be prepared in accordance with the procedures set forth in co-pending application, Ser. No. 228,384, filed Oct. 4, 1962 in the names of Gordon A. Hughes and Herchel Smith, and in co-pending application, Ser. No. 310,484, filed Sept. 20, 1963 in the names of Kurt W. Ledig and Gerhard R. Wendt, now abandoned.

According to a feature of this invention, the final products (compounds of Formula I) may be prepared by introducing a nitrate ester group in the compounds of Formula II, as by treatment with silver nitrate in an inert organic medium (e.g., acetonitrile), in the presence of iodine.

Among the suitable starting steroids that are utilizable in the process of the invention may be mentioned

- 45 13-lower alkyl-17 β -lower alkenyloxy-3-alkoxygona-1,3,5(10)-triene (e.g., 13-methyl-17 β -(3-buten-1-oxy)-3-methoxygona-1,3,5(10)-triene, 13-ethyl-17 β -allyloxy-3-methoxygona-1,3,5(10)-triene, 50 13-ethyl-17 β -allyloxy-3-ethoxygona-1,3,5(10)-triene, 13-propyl-17 β -(2-buten-1-oxy)-3-ethoxygona-1,3,5(10)-triene, 13-propyl-17 β -allyloxy-3-methoxygona-1,3,5(10)-triene, 55 13-butyl-17 β -(2-penten-1-oxy)-3-propoxygona-1,3,5(10)-triene); 17 β -lower alkenyloxy-3-alkoxyestra-1,3,5(10)-triene (e.g., 17 β -(2-buten-1-oxy)-3-methoxyestra-1,3,5(10)-triene, 17 β -allyloxy-3-methoxyestra-1,3,5(10)-triene, 60 17 β -allyloxy-3-ethoxyestra-1,3,5(10)-triene, 17 β -(3-buten-1-oxy)-3-methoxyestra-1,3,5(10)-triene, 17 β -(2-penten-1-oxy)-3-butoxyestra-1,3,5(10)-triene); 17 β -alkenyloxy-3-acyloxyestra-1,3,5(10)-triene (e.g., 17 β -(2-buten-1-oxy)-3-hydroxyestra-1,3,5(10)-triene-3-acetate, 65 17 β -allyloxy-3-hydroxyestra-1,3,5(10)-triene-3-acetate); 17 β -lower alkenyloxy-13-lower alkyl-3-acyloxygona-1,3,5(10)-triene (e.g., 17 β -(2-buten-1-oxy)-13-ethyl-3-hydroxygona-1,3,5(10)-triene-3-acetate, 70 17 β -allyloxy-13-ethyl-3-hydroxygona-1,3,5(10)-triene-3-acetate), and the like.

3

The following examples illustrate the invention (all temperatures being in centigrade).

EXAMPLE 1

17 β -(2,3-dihydroxypropoxy)-3-methoxyestra-1,3,5(10)-triene, dinitrate

To 1.1 gm. of 17 β -allyloxy-3-methoxyestra-1,3,5(10)-triene in 25 ml. of acetonitrile is added 1.2 gm. of silver nitrate. The mixture is then stirred and refluxed while 0.5 gm. of iodine is added over a period of 15 minutes. The mixture is refluxed additionally for one hour. The reaction mixture is cooled, filtered and the filtrate is diluted with water. The filtrate is then extracted with ether. The organic layer is washed with an aqueous sodium bisulfite solution and the solvent is evaporated in vacuo. The residue is chromatographed in a benzene-hexane (3:7) solution over Florex. The elution with benzene yielded 17 β -(2,3-dihydroxypropoxy)-3-methoxyestra-1,3,5(10)-triene, dinitrate.

$\lambda_{\text{max}}^{\text{sum}}$ 6.10, 7.85, ($-\text{O}-\text{NO}_2$) μ ;

Analysis.—Calcd. for C₂₂H₃₀N₂O₆: C, 58.65; H, 6.71; N, 6.22. Found: C, 58.40; H, 6.62; N, 6.23.

EXAMPLE 2

17 β -(2,3-dihydroxypropoxy)-3-ethoxyestra-1,3,5(10)-triene, dinitrate

Following the procedure of Example 1 but substituting 17 β -allyloxy-3-ethoxyestra-1,3,5(10)-triene for 17 β -allyloxy-3-methoxyestra-1,3,5(10)-triene there is obtained 17 β -(2,3-dihydroxypropoxy)-3-ethoxyestra-1,3,5(10)-triene, dinitrate.

EXAMPLE 3

3-acetoxy-17 β -(2,3-dihydroxypropoxy)-estra-1,3,5(10)-triene, dinitrate

Following the procedure of Example 1 but substituting 17 β -allyloxy-3-hydroxyestra-1,3,5(10)-triene-3-acetate for 17 β -allyloxy-3-methoxyestra-1,3,5(10)-triene there is obtained 3-acetoxy-17 β -(2,3-dihydroxypropoxy)-estra-1,3,5(10)-triene, dinitrate.

EXAMPLE 4

17 β -(2,3-dihydroxybutoxy)-3-methoxyestra-1,3,5(10)-triene, dinitrate

Following the procedure of Example 1 but substituting 17 β -(2-buten-1-oxy)-3-methoxyestra-1,3,5(10)-triene for 17 β -allyloxy-3-methoxyestra-1,3,5(10)-triene there is obtained 17 β -(2,3-dihydroxybutoxy)-3-methoxyestra-1,3,5(10)-triene, dinitrate.

EXAMPLE 5

3-acetoxy-17 β -(3,4-dihydroxypentoxo)-estra-1,3,5(10)-triene, dinitrate

Following the procedure of Example 1 but substituting 17 β -(3-penten-1-oxy)-3-hydroxyestra-1,3,5(10)-triene-3-acetate for 17 β -allyloxy-3-methoxyestra-1,3,5(10)-triene there is obtained 3-acetoxy-17 β -(3,4-dihydroxypentoxo)-estra-1,3,5(10)-triene, dinitrate.

EXAMPLE 6

13-ethyl-17 β -(2,3-dihydroxypropoxy)-3-methoxy-gona-1,3(10)-triene, dinitrate

Following the procedure of Example 1 but substituting 17 β -allyloxy-13-ethyl-3-methoxygona-1,3,5(10)-triene for 17 β -allyloxy-3-methoxyestra-1,3,5(10)-triene there is obtained 13-ethyl-17 β -(2,3-dihydroxypropoxy)-3-methoxygona-1,3,5(10)-triene, dinitrate.

EXAMPLE 7

13-ethyl-17 β -(2,3-dihydroxypropoxy)-3-ethoxygona-1,3,5(10)-triene, dinitrate

Following the procedure of Example 1 but substituting 13-ethyl-17 β -allyloxy-3-ethoxygona-1,3,5(10)-

4

triene for 17 β -allyloxy-3-methoxyestra-1,3,5(10)-triene there is obtained 13-ethyl-17 β -(2,3-dihydroxypropoxy)-3-ethoxygona-1,3,5(10)-triene, dinitrate.

EXAMPLE 8

3-acetoxy-13-ethyl-17 β -(2,3-dihydroxypropoxy)-gona-1,3,5(10)-triene, dinitrate

Following the procedure of Example 1 but substituting 13-ethyl-17 β -allyloxy-3-hydroxygona-1,3,5(10)-triene-3-acetate for 17 β -allyloxy-3-methoxyestra-1,3,5(10)-triene there is obtained 3-acetoxy-13-ethyl-17 β -(2,3-dihydroxypropoxy)-gona-1,3,5(10)-triene, dinitrate.

EXAMPLE 9

3-acetoxy-13-propyl-17 β -(2,3-dihydroxypropoxy)-gona-1,3,5(10)-triene, dinitrate

Following the procedure of Example 1 but substituting 13-propyl-17 β -allyloxy-3-hydroxygona-1,3,5(10)-triene-3-acetate for 17 β -allyloxy-3-methoxyestra-1,3,5(10)-triene there is obtained 3-acetoxy-13-propyl-17 β -(2,3-dihydroxypropoxy)-gona-1,3,5(10)-triene, dinitrate.

EXAMPLE 10

3-acetoxy-13-butyl-17 β -(2,3-dihydroxypropoxy)-gona-1,3,5(10)-triene, dinitrate

Following the procedure of Example 1 but substituting 13-butyl-17 β -allyloxy-3-hydroxygona-1,3,5(10)-triene-3-acetate for 17 β -allyloxy-3-methoxyestra-1,3,5(10)-triene there is obtained 3-acetoxy-13-butyl-17 β -(2,3-dihydroxypropoxy)-gona-1,3,5(10)-triene, dinitrate.

EXAMPLE 11

3-acetoxy-13-propyl-17 β -(2,3-dihydroxypentoxo)-gona-1,3,5(10)-triene, dinitrate

Following the procedure of Example 1 but substituting 13-propyl-17 β -(2-penten-1-oxy)-3-hydroxygona-1,3,5(10)-triene-3-acetate for 17 β -allyloxy-3-methoxyestra-1,3,5(10)-triene there is obtained 3-acetoxy-13-propyl-17 β -(2,3-dihydroxypentoxo)-gona-1,3,5(10)-triene, dinitrate.

EXAMPLE 12

3-acetoxy-13-butyl-17 β -(3,4-dihydroxypentoxo)-gona-1,3,5(10)-triene, dinitrate

Following the procedure of Example 1 but substituting 13-butyl-17 β -(3-penten-1-oxy)-3-hydroxygona-1,3,5(10)-triene-3-acetate for 17 β -allyloxy-3-methoxyestra-1,3,5(10)-triene there is obtained 3-acetoxy-13-butyl-17 β -(3,4-dihydroxypentoxo)-gona-1,3,5(10)-triene, dinitrate.

EXAMPLE 13

3-cyclopentoxy-17 β -(2,3-dihydroxypropoxy)-estra-1,3,5(10)-triene, dinitrate

Following the procedure of Example 1 but substituting 3-cyclopentoxy-17 β -allyloxy-estra-1,3,5(10)-triene for 17 β -allyloxy-3-methoxyestra-1,3,5(10)-triene there is obtained 3-cyclopentoxy-17 β -(2,3-dihydroxypropoxy)-estra-1,3,5(10)-triene, dinitrate.

EXAMPLE 14

3-cyclohexyloxy-13-ethyl-17 β -(2,3-dihydroxybutyloxy)-gona-1,3,5(10)-triene, dinitrate

Following the procedure of Example 1 but substituting 3-cyclohexyloxy-13-ethyl-17 β -(2-buten-1-oxy)-gona-1,3,5(10)-triene for 17 β -allyloxy-3-methoxyestra-1,3,5(10)-triene there is obtained 3-cyclohexyloxy-13-ethyl-17 β -(2,3-dihydroxybutyloxy)-gona-1,3,5(10)-triene, dinitrate.

The invention may be variously otherwise embodied within the scope of the appended claims.

What is claimed is:

1. A compound of the formula:

wherein R is selected from the group consisting of a lower alkyl of 1 to 2 carbon atoms, acetyl, cyclopentyl, and cyclohexyl; R¹ is a lower alkyl group of 1 to 4 carbon atoms; R² is selected from the group consisting of hydrogen and a lower alkyl of 1 to 2 carbon atoms; and n is a number from 1 to 2.

2. A compound of claim 1, having the structural formula:

in which R is a lower alkyl of 1 to 2 carbon atoms, acetyl or cyclopentyl and R¹ is a lower alkyl of 1 to 4 carbon atoms.

3. A compound according to claim 1 wherein R is methyl; R¹ is methyl; R² is hydrogen and n is 1.

4. A compound according to claim 1 wherein R is methyl; R¹ is ethyl; R² is hydrogen and n is 1.

5. A compound according to claim 1 where R is cyclohexyl; R¹ is ethyl; R² is methyl and n is 1.

10 6. A compound according to claim 1 wherein R is cyclopentyl; R¹ is ethyl; R² is hydrogen and n is 1.

7. A compound according to claim 1 wherein R is acetyl; R¹ is methyl; R² is hydrogen and n is 1.

15 8. A compound according to claim 1 wherein R is acetyl; R¹ is ethyl; R² is hydrogen and n is 1.

9. A compound according to claim 1 wherein R is acetyl; R¹ is ethyl; R² is methyl and n is 1.
